(57) **CLAIM**

I claim the ornamental design for a pill box, as shown and described.

DESCRIPTION

FIG. 1 is a bottom perspective view of a pill box, showing a first embodiment of my new design in an open position;
FIG. 2 is a top perspective view of FIG. 1;
FIG. 3 is a bottom perspective view thereof, illustrated in a closed position;
FIG. 4 is a front elevational view of FIG. 3;
FIG. 5 is a rear elevational view of FIG. 3;
FIG. 6 is a left-side elevational view of FIG. 3, the right-side elevational view being a mirror image thereof;
FIG. 7 is a top plan view of FIG. 3;
FIG. 8 is a bottom plan view of FIG. 3;
FIG. 9 is a bottom perspective view of a second embodiment thereof, illustrated in the open position; and,
FIG. 10 is a top perspective view of FIG. 9.
The broken lines showing pills in the figures and a necklace in FIG. 1 depict environmental matter and form no part of the claimed design. It is understood that both embodiments appear identical when each is in the closed position.
